UNITED STATES PATENT OFFICE.

EDWIN R. HEARN, OF JERSEY CITY, NEW JERSEY, ASSIGNOR TO P. LORILLARD & CO., OF SAME PLACE.

MACHINE FOR DRYING LEAF-TOBACCO.

SPECIFICATION forming part of Letters Patent No. 229,126, dated June 22, 1880.

Application filed October 4, 1879.

To all whom it may concern:

Be it known that I, EDWIN R. HEARN, of Jersey City, in the county of Hudson and State of New Jersey, have invented certain new and useful Improvements relating to Machines for Drying Leaf-Tobacco, of which the following is a specification.

It is especially adapted for drying the material at a certain stage in the manufacture of a fine quality of chewing-tobacco by first subjecting it to a current of warm air and afterward cooling and completing the drying by a current of cold air, thus avoiding the exposure of the delicate material to long-continued warmth. I will describe the apparatus as thus worked.

The following is a description of what I consider the best means of carrying out the invention.

2c The accompanying drawings form a part of this specification.

Figure 1 is a general side elevation; Fig. 2, a plan view, and Fig. 3 a vertical section. Figs. 4 and 5 are vertical sections in planes at right angles to Fig. 3. Fig. 4 is on the line Y Y, and Fig. 5 is on the line Z Z in Figs. 1 and 3. Figs. 6 and 7 show certain portions of the same on a larger scale. Fig. 6 is a part of the section shown in Fig. 4. Fig. 7 is a part of the section shown in Fig. 5.

Similar letters of reference indicate like parts in all the figures.

The drying apparatus is formed with hollow chambers or sections side by side, having currents of air rising in each. The tobacco-leaf is introduced on racks of wire-netting, which may be nearly similar to those long used in kilns or drying-rooms, but a little deeper. The racks should be about five feet long and 40 two feet wide, the bottom or body of wire-netting, and the sides and ends of wood—say four inches high and half an inch thick—with the netting nearly half-way up in the inclosing wood frame. These racks, each carrying a proper quantity of the tobacco-leaf, are piled one upon another and caused to slowly descend in one section of the apparatus. The attendant continually adds fresh racks at the top. The racks at the bottom are moved across

from the bottom of this first pile to the bottom of an adjacent pile in the adjoining section, where it commences to be elevated. This second pile is slowly elevated, the top ones being successively removed.

In carrying out the invention I make one 55 revolving shaft give all the motions by a very simple mechanism. I attach importance not only to the motions ultimately attained, but also to the simplicity of the mechanism by which these varied motions are secured.

Referring to the drawings, the single letter A is used to designate the entire stationary parts. I will designate the chambers or spaces as a' a², &c., in which the racks B, supporting the tobacco, are received to be subjected to the 65 treatment for drying and cooling.

The bottom of the first chamber, a', receives a current of warm dry air through a pipe, m, from a blower and heater, (not represented;) but it may be of any ordinary or suitable 70 character.

The bottom of the next chamber, a², is connected by a pipe, n, to another blower, (not represented,) which forces an active current of cold air into the bottom of said second chamber, a². The air rising through each bears away some of the moisture and causes it to be discharged through any suitable flue into the atmosphere.

The air rising in the second chamber, a², is 80 cold, and when the tobacco, which is warmed in its descending movement through the first chamber, a', is again cooled in its ascending movement in the chamber a², it arrives at the end of its route dried to the proper condition, 85 and also cooled.

The first chamber, a', is kept filled with racks, which rest one upon another, and descend intermittently as each is successively removed on reaching the bottom. A transferring mechanism moves the last rack horizontally forward and introduces it into the next pile, so that it forms the bottom rack thereof. In this pile it is lifted successively by the constant introduction of fresh racks underneath until 95 it appears at the top, when it is again moved horizontally forward either on a new descending pile, as above described, or to be directly

discharged upon an inclined chute, A', as here shown.

Either way the operation is automatic and continuous for an indefinite period.

5 D is a constantly-revolving shaft driven by a pulley, d, which receives motion by a belt from a steam-engine or other power. (Not represented.)

D' D' are cams keyed on the shaft D. They 10 act on cross-yokes E, each of which carries two vertical rods, e' e², grooved in the inside of the respective chambers a' a². The lower end of each rod e' e² is formed with a mortised enlargement or strap, which contains a movable slide or catch, serving at proper times as an inward projection or hook. The effects of 15 the working of the rods e' e² e² are substantially different, e' and their contained catches e* being adapted to lower the racks which rest on them, while e² and their contained catches e** are adapted to raise the racks which rest on them. All reciprocate vertically at the same time. The catch mounted in the lower end of 20 each rod e' and e² is beveled from the inner face on the lower side.

25 As the yoke E sinks, the catches e** in the rods e² are forced inward by striking the fixed cam-surfaces A**, and it follows, from the beveled under side and square upper side of 30 the catches e**, that at each descent of the yokes E, and consequently of the rods e², the catches at the bottom of these rods snap under and engage with the lowermost rack. At each ascent of the same parts the tier of racks 35 in the chamber a² are lifted. During the period while they are lifted a rack is transferred from the other chamber, a', so that on the next descent the tier remains elevated in consequence of the accession below, and on the 40 next descent of the rods e² they engage that bottom one and lift it, and so on in succession. The other chamber, a', has fixed stops A*, which force back the catches at each descent, and cause them to lower instead of raise the 45 racks. In the last part of the ascending motion of the yoke E the rods e' e' engage their transverse sliding catches or projections e* e* under the next to the lowermost rack B by being forced inward by the fixed cam-surfaces 50 Z* and slightly lift the whole tier above. The lowermost rack is then pushed across under the other pile by means to be presently described. Now, on the lowering motion which follows, the descent of the rods e' lowers the 55 tier of racks B, with their contents, steadily and moderately until the lowest is near the bottom of the chamber a'. At that point the cross slide or catch e^x in each rod e' is deflected outward or moved away from the racks 60 by its beveled inner side striking against a fixed stop, A*. So soon as this deflection has been carried to a sufficient extent the catches or projections e* become disengaged and allow the whole tier of racks to fall. I take care 65 that the fall thus induced shall be only a fraction of an inch, so as to induce no mischief.

On the ascent of the rods e' their catches e*

miss the lowest rack and engage under the next rack and again slightly lift it, and again allow the one below to be removed; then the 70 operation of lowering is repeated.

The transference is effected by rods g, which reciprocate in horizontal grooves in the sides of the chambers close to the bottom. On the end of each is a projection, g*, having one 75 side squared and the other beveled, as shown. Each rod springs inward a little, and at each movement in one direction the projection g* slides idly across, but on the return motion the projection engages with its square face 80 against the corners of the lowermost rack and carries it with it. There is a sufficient opening at the bottom of the partition between the chambers a' a² to allow the rack to be thus transferred across under it. A similar pair of 85 rods, h, provided with projections h*, is traversed on each side at the top of the chambers a' a². These rods effect the automatic removal of the top rack from the ascending tier.

I effect the horizontal movement of both the 90 pairs of rods, g and h, as follows: Both pairs are harnessed together by a yoke, F, and both are moved simultaneously by means of links I, which connect from a pivot, f, on the yoke to another pivot, j', on the lower end of a peculiarly-curved lever, J, which lever turns on a fixed center, j, on the outside of the box. The arms D², carrying projections or crank-pins d², are keyed on the shaft D, and the parts are so arranged that at each revolution of the shaft 100 D each projection d² strikes the lever J below the curve therein and moves the lever forward until the projections d² enter the curved recesses in the corresponding levers J and are no longer effective. A little later the rotation 105 of the shaft D brings the projections d² into contact with another set of levers, K, which are adapted to compel the return motion. This set of levers are bell-crank in form, and turn on fixed centers k, and act on the latter by 110 means of anti-friction rollers k'. The projections d² strike the short horizontal arms of the levers K and move them upward. This motion causes the long arm carrying the rollers k' to act each on the corresponding levers J, 115 to induce the proper return motion.

I have represented the lower ends of the levers K as tied to the respective levers J by a slight link, k², embracing the latter. I prefer this construction, but I do not esteem it absolutely essential. This construction and arrangement of the levers J and K affords, in combination with the revolving shaft D and the connected projections d², a reliable and simple means of inducing the proper reciprocation of the rods g and h, and consequently 125 the proper horizontal motions of the racks at the proper times. It allows a long period of rest while the projections d² are sweeping idly around from the vicinity of the center j—something like a half of a revolution. The entire movements of the racks F, and consequently of the rods g and h and the two racks engaged respectively thereby, are effected during less 130

than half of a revolution of the shaft B. The cams D' are so formed that they hold the yokes E and the tier of racks in each of the chambers a' a² steadily up during the entire period 5 while the transference is being effected.

Having thus minutely described the action with only two chambers, a' a², and two piles of racks therein, it may not be necessary to elaborately describe the action when there are 10 more than two. I have devised means to not only move the top rack of this ascending pile horizontally, but also by the same movement to introduce it upon another pile of descending racks, to be again transferred across at 15 the bottom and again elevated in another pile. This operation may be still further repeated, if preferred. It is simply necessary to extend the apparatus and so arrange it that the transference effected by the rods h of the top rack 20 from the pile in a² places the rack on the top of the tier in the next chamber succeeding.

Modifications may be made in many of the details.

If I use only one pair of chambers, the motion of the racks B must be sufficiently slow to allow the drying to be properly effected at one descent and elevation; but if I use two or three sets of chambers, so as to hold the tobacco in the machine longer, treating it all the 25 time with the drying air, I can make the motion of the machinery much more rapid, and consequently treat the tobacco much faster with a given size of machine.

I can, with any or all the forms of the apparatus, supply both the chambers a' a² with a 30 current of warm air. In such case the drying will be considerably more rapid in an apparatus of a given size and capacity. For many kinds of tobacco this will be the preferable 35 mode of working. To thus work, the only change from the above description is to supply warm air instead of cold through the pipe n.

I claim as my invention—

1. In a machine for drying tobacco or analogous material, the case A, with the chambers a' a², and a series of racks, B, with automatic mechanism, substantially as described, for moving them in such chambers, all substantially as herein specified.

50 2. In a machine for drying tobacco or analogous material by blowing currents of air through or among the same, the chambers a' a²,

in combination with each other and with devices, e' e², for automatically lowering a series of racks in the chamber a' and for automatically raising a corresponding series in the chamber a², all arranged for joint operation as and for the purposes herein specified. 55

3. The machine described, having in combination, first, provisions for circulating air 60 through two or more chambers in a fixed casing; second, separate portable racks for presenting the tobacco therein; and, third, automatic machinery for transferring said racks down through the first chamber, across the bottom, 65 and up through the second chamber, all substantially as and for the purposes specified.

4. In a drying-machine, the shaft D, cams D', yokes E, rods e' e², and projections e* e**, in combination with each other and with the 70 case A, having chambers a' a², and with racks B, substantially as herein specified.

5. Means, e' e² e* e**, for raising and lowering the racks B therein, means, m n, for blowing away the moisture, and means, g h, for transferring the racks horizontally at the bottom and at the top of the several tiers, in combination with each other and with the case A, having chambers a' a², substantially as and for the purposes herein specified. 75

6. In a machine for treating tobacco and analogous material, the levers J and K, arranged as shown, in combination with the revolving shaft B, carrying the cranks or projections b², and with the connected devices, g 85 and h, for effecting the horizontal movements of the racks at the top and bottom of the tiers, as herein specified.

7. The combination, in a tobacco-treating machine, of the shaft D, cams D', arms D², 90 yokes E, rods e' e², and projections e*, and also with the arms D², pins d², levers J and K, links I, yokes E F, and rods g and h, with their projections e* g*, arranged for joint operation relatively to each other and to the casing A, having the chambers a' a², containing the racks B, 95 as and for the purposes herein specified.

In testimony whereof I have hereunto set my hand this 11th day of September, 1879, in the presence of two subscribing witnesses. 100

EDWIN R. HEARN.
